RUDOLPH B. MICHALEK, OF NEWARK, NEW JERSEY.

TOY GUN.

1,338,458.

Specification of Letters Patent. Patented Apr. 21

Application filed August 5, 1919. Serial No. 315,413.

To all whom it may concern:

Be it known that I, RUDOLPH B. MICHALEK, a citizen of Czechoslovakia, and a resident of Newark, county of Essex, and 5 State of New Jersey, have invented certain new and useful Improvements in Toy Guns, of which the following is a specification.

This invention relates particularly to a toy gun that simulates the fire of a rapid 10 fire or machine gun, and is of the type that employs a feed wheel which feeds a strip of caps and at the same time intermittently operates a hammer to explode the caps after they have passed the feeding wheel.

15 The invention is designed to provide a gun of this kind in which the caps are easily inserted, the feeding is initiated without difficulty or annoyance and in which the handle for operating the device is so disposed relative to the opening through which 20 the exploded caps emerge that there is no possibility of burning the hand.

Another object of the invention is to provide a gun which can simulate a machine 25 gun by reason of the fact that it is swiveled to a suitable block or other support.

The invention further consists in the arrangement and relative positioning of the parts to form a combination to permit 30 economy of manufacture and to provide a compact and stable toy, the details of which are more fully described hereinafter and finally embodied in the claims.

The invention is illustrated in the accompanying drawing, in which Figure 1 illustrates a top view of my improved toy gun, with the strip holder broken away to more clearly illustrate the mechanism within. Fig. 2 is a side view of the gun shown in 40 Fig. 1, with the casing broken away at the central portion thereof, and with the strip holder in open position, and Fig. 3 is a vertical section of a part of the gun taken on the plane approximately represented by 45 line 3-3 in Fig. 2, showing the parts within the casing in elevation.

The main part of the gun is made up of a casing that usually consists of two halves 10 and 11, this being the preferred way of making it, because the two halves can be more easily made and easily assembled, these halves being divided longitudinally and substantially central of the gun. The general outline of the gun is designed to 50 provide a barrel part 12 that has the appearance of being the barrel of the gun, and

a support 13 which is substantially disposed and on the back is a handle portion 14. The support terminates in a hollow bottom part gun is suitably mounted, but it is 1 to arrange it so that it can be swiv 20 zontally, and to permit such swiv 25 is placed on a base plate 16, which is tened to a pedestal or other suitable 17 by means of a pivotal screw 1 27 side of the gun, and a guiding 28 on the other side of the gun passes a slot 20 in the base plate; in this 30 swinging of the gun being possible 35 expense of manufacture is low.

The casing is usually made of 40 or sheet metal and for the most 45 hollow, the support 13 being 50 provide for a reduction in weight 55 for more graceful outline, and w 60 support is a hammer 21, operat 65 spring to yieldingly hold it and to 70 it against a suitable striking 75 that the caps are exploded.

In the form shown, the hammer 80 is operated by the pin 22 and has an ext 85 which extends back in the base p 90 a spring 24 resting against the 95 the extension and having another 100 ing against the bottom plate 25 or portion 15, so that the hammer 105 mally forced forward. The hammer 110 against an anvil, which, in the for 115 is provided by a stop 26 against 120 end 27 of a spring 28 rests, the 125 passing over a bar 29 and havir 130 adapted to bear against the 135 the cap strip holder 32, which hub 140 by a suitable pin 33. The sprin 145 held in place and at the same tir 150 vides suitable friction to prevent 155 ping of the strip holder 32, the int 160 portion of the spring, that is, th 165 between the bar 29 and the stop 170 utilized as a surface against which 175 ining of the strip is accomplished, 180 described hereinafter.

The strip holder is preferably 185 on its end with a suitably forme 190 which, when the strip holder is 195 against the inner side of the cas 200 strip holder is adapted to receiv 205 strip of caps and has a top piece 210 provided with a pin 36 around 215 cap strip is placed, and the latte 220 what loosely wound so that it is

stalled in the strip holder. The end 37 of the plate 34 is usually made long enough so that it engages a boss into which the connecting screw 38 is screwed to hold the two 5 halves of the casing together, the downward movement of the strip holder thus being limited and the strip holder does not pass beyond the point where its outline is in register with the outline of the casing, and 10 when the strip holder is closed there is thus provided a symmetrical exterior.

A feeding wheel 39 is journaled between the two sides of the casing and is disposed so that when it is rotated it will feed the 15 strip of caps along the surface of the spring 28, the feed wheel being suitably rotated, a steady rotation being preferred which is provided by means of a crank handle 40, the arm 41 of which is connected with the axle 20 42, the axle being secured to or integral with the feeding wheel 39 and also with a set of fingers 43, this set of fingers being to one side and in line with the nose 44 on the end of the hammer 21, the spring 28 being 25 cut away to permit the rotation of the fingers 43, or the spring can be made narrower than the casing to permit such rotation.

It will thus be seen that when a strip of caps is placed in the strip holder, the end 30 thereof is placed between the feeding wheel 39 and the intermediate portion of the spring 28, and a very slight turn gives it enough grip so that it is securely held after the initial entrance has been effected. The 35 strip holder is then closed, and by rotating the handle 40 the strip is fed forward, the fingers 43 successively engaging the nose 44 of the hammer and pulling the hammer back to a point where the finger will clear the end 40 of the nose 44, and then the spring 24 snaps the hammer so that it is forced against the anvil formed by the stop 26 and the end of the spring 28, and the cap is exploded and the fragments of the strip and the cap pass 45 out through the opening 45.

The handle 40 is so disposed relative to the fingers 43 that it is not opposite the opening 45 when the hammer is released, this preferred disposition being made so that 50 the hand is not in position to receive any sparks from the explosion of a cap when passing the opening when such explosion takes place. Burns from such explosions are, however, not possible because the side 55 pieces of the gun are not broken away, the opening 45 being in the front of the support 13. The rest of the gun is closed and there is no likelihood of any injury or damage resulting from the use of it in the way 60 in which it is designed to be used, and the assembly and manufacture of the parts of

the gun are easy and economical. 28 provides a smooth surface on which the strip travels, and it also acts as a guide to the paper strip as it emerges from the gun, the other end of the strip being held by the hub 21, thereby performing the function of a pressure means on the strip and also providing a compact structure.

I claim:

1. A toy gun comprising a support, a hammer pivoted in an extension on the hammer, a feeding wheel on the bottom of the support, the extension, a feeding wheel, a support, a set of fingers projecting to the wheel, a nose on the hammer so as to be engaged by the fingers, a stop in the casing, a bar, a spring resting against the bar and having its intermediate portion adapted to form a surface for receiving a strip of caps engaged by the wheel, and means for rotating the wheel.

2. In a toy gun, a hammer means for a strip of caps, a spring which the feeding means and the hammer operate, and a strip holder inclined on which the holder swings, the spring being arranged to bear on the holder.

3. In a toy gun, a feeding wheel, a spring against which the wheel and the hammer are operated, over which the spring is curved, the holder including a hub, the end of the spring being curved after passing the bar bearing against the hub to give the spring a tension after the feeding means operate and the tension on the strip holder.

4. A toy gun comprising a casing, a support, the front of the support, a strip holder pivoted in the top of the casing, the casing just above the opening having a stop, a spring resting against a bar near the top of the casing, the spring being curved, the strip holder having a hub against which the spring bears, the curved portion bears, a hammer, a feeding wheel, the feeding wheel bearing the spring between the stop and the handle for rotating the feeding wheel, the fingers rotated with the feeding wheel being adapted to be successively engaged by the fingers to trip the hammer and a spring bearing against the hammer to snap it to its normal position.

In testimony that I claim the invention I have hereto set my hand this 13th day of August, 1919.

RUDOLPH B. MICHAEL
